UNITED STATES PATENT OFFICE

107,222

DESIGN FOR A TOY TELEPHONE

George Dobrusin, Chicago, Ill.

Application September 16, 1937, Serial No. 71,644

Term of patent 7 years

To all whom it may concern:

Be it known that I, George Dobrusin, a citizen of the United States, and a resident of Chicago, in the county of Cook and State of Illinois, have invented a new, original, and ornamental Design for a Toy Telephone, of which the following is a specification, reference being had to the accompanying drawing, forming a part thereof, and in which:

Fig. 1 is a perspective view of a toy telephone showing my new design;

Fig. 2 is an elevational view of the same as seen along lines 2—2 of Fig. 1; and

Fig. 3 is a view looking up in the direction of lines 3—3 of Fig. 1.

I claim:

The ornamental design for a toy telephone, as shown.

GEORGE DOBRUSIN.
